(57) **CLAIM**

We claim, the ornamental design for a lighting fixture, as shown and described.

DESCRIPTION

This application is related to commonly assigned, co-filed U.S. design patent application Ser. No. 29/791,126, filed on Dec. 30, 2021 by Daniel A. Montecino and Robert E. De'Armond, Jr., entitled "Lighting Fixture", which application is incorporated herein by reference in its entirety.

FIG. 1 is a front right perspective view from above of a lighting fixture according to the new design;

FIG. 2 is a rear left perspective view from below thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof;

FIG. 9 is a front right perspective view from above thereof, but shown illuminated;

FIG. 10 is a rear left perspective view from below thereof;

FIG. 11 is a front elevational view thereof;

FIG. 12 is a right side elevational view thereof;

FIG. 13 is a left side elevational view thereof;

FIG. 14 is a rear elevational view thereof;

FIG. 15 is a top view thereof; and,

FIG. 16 is a bottom view thereof.

The broken lines in the drawings illustrate portions of the environment and the lighting fixture and form no part of the claimed design.

The stippling shown in FIGS. 9, 10, 15, and 16 is solely for the purpose of illustrating the appearance of illumination and does not represent texture or surface ornamentation.

The long dash-short dash lines in the drawings represent a boundary of the claimed design.
